UNITED STATES PATENT OFFICE

JOHN KIRKPATRICK, OF CLARKSBURG, WEST VIRGINIA, ASSIGNOR TO HAZEL-ATLAS
GLASS CO., OF WHEELING, WEST VIRGINIA, A CORPORATION OF WEST VIRGINIA

DESIGN FOR AN ASH TRAY

Application filed November 3, 1930. Serial No. 37,509. Term of patent 3½ years.

To all whom it may concern:

Be it known that I, JOHN KIRKPATRICK, a citizen of the United States, residing at Clarksburg, in the county of Harrison and State of West Virginia, have invented a new, original, and ornamental Design for an Ash Tray, of which the following is a specification, reference being had to the accompanying drawings, forming part thereof.

Figure 1 is a plan view of an ash tray; and Figure 2 is a vertical sectional view thereof, showing my new design.

I claim:

The ornamental design for an ash tray, as shown.

JOHN KIRKPATRICK.
